UNITED STATES PATENT OFFICE.

JULIUS J. MILLER, OF ST. JOSEPH, MICHIGAN.

INTERNAL-COMBUSTION-ENGINE IGNITION-INDICATOR.

1,313,319.

Specification of Letters Patent. Patented Aug. 19, 1919.

Application filed August 27, 1917. Serial No. 188,294.

To all whom it may concern:

Be it known that I, JULIUS J. MILLER, a citizen of the United States of America, and resident of St. Joseph, Michigan, have invented a certain new and useful Improvement in Internal-Combustion-Engine Ignition-Indicators, of which the following is a specification.

My invention relates to devices for use in connection with the ignition systems of internal combustion engines, such as those used on automobiles, and more particularly to those for use in connection with internal combustion engines having a plurality of cylinders.

One object of my invention is to provide an improved indicator which will show whether the spark plugs of the different cylinders are properly receiving current, or whether some particular spark plug is receiving no current, thus indicating which engine cylinder is out of use.

Another object is to provide an improved indicator of this character which will serve also as a spark intensifier for the spark plugs of the ignition system.

Another object is to provide an improved indicator connected with the ignition system and provided with means for at will controlling the supply of current to the different spark plugs, so that the current can be cut off from any spark plug at will, thereby to determine which cylinder is out of use or running without explosion of the fuel therein.

It is also an object to provide certain details and features of construction and combinations tending to increase the general efficiency and desirability of an ignition indicator of this particular character.

To the foregoing and other useful ends my invention consists in matters hereinafter set forth and claimed.

In the accompanying drawings:

45 Figure 1 is a diagram showing the application of an indicator embodying the principles of my invention to the ignition system of an automobile.

Fig. 2 is a front elevation of said indicator.

Fig. 3 is a transverse vertical section of line 3—3 in Fig. 2.

Fig. 4 is a rear elevation of the indicator.

Fig. 5 is a detail section on line 5—5 in

55 Fig. 4.

Fig. 6 is a detail section on line 6—6 in Fig. 4.

As thus illustrated, the engine A of the automobile may be of any suitable character, and in this case is shown as having four 60 cylinders. The ordinary ignition system, whereby electric current is supplied to the spark plugs 1, 2, 3 and 4 of said engine, involves the usual distributor B, having binding posts 5, 6, 7 and 8, which correspond to 65 said spark plugs, in the usual and well-known manner. The four connections 9, however, which lead from the spark plugs, instead of being connected to said distributor, in the ordinary manner, are connected 70 in proper order to the four screws 10, 11, 12 and 13 of the indicator C, which latter is mounted on the dash of the automobile. The four connections 14 leading from the distributor B, instead of being connected to 75 the spark plugs, are connected in proper order to the upper points or electrodes 15, 16, 17 and 18, which are arranged directly above and in line with the screws 10, 11, 12 and 13, being suitably supported in the insulating material which forms the body of the indicator. Thus the screws 10, 11, 12 and 13, and their corresponding points or electrodes 15, 16, 17 and 18, provide spark gaps in the circuits of the spark plugs, so that the 80 current for each plug must jump a gap in the indicator, whereby the current or sparking action is made visible to the driver or occupant of the automobile. The front portion of the indicator body is provided with 90 four holes 19, 20, 21 and 22, and a glass plate 23 is arranged over these holes, whereby windows are provided for exposing to view the spark gaps, so that the sparking action is 95 in plain view. A longitudinal slide 24, of insulating material, is provided at its end with a handle 25, and this slide is provided with metal inserts 26 and with notches 27, whereby the spark gaps are each operative 100 to produce a visible sparking action when 100 notches 27 are opposite their respective spark gaps, and whereby this electrical sparking action will stop as soon as the slide 24 is shifted sufficiently to bring the metal inserts 26 into the spark gaps, it being understood 105 that these inserts can be made to fit snugly in the gaps provided between the screws 10, 11, 12 and 13 and the points or electrodes 15, 16, 17 and 18, when the slide is shifted for 110 this purpose. The screws 10, 11, 12 and 13

can be adjusted up and down, obviously, to regulate the spark gaps. Furthermore, a metal strip 28 extends across the front of the indicator, adjacent the electrodes 15, 16, 17 and 18, and is provided with metal springs 29 to be operated by push buttons 30, whereby any one of these springs can be pushed into contact with any one of the adjacent points or electrodes 15, 16, 17 and 18, thereby making electrical contact with the latter. The strip 28 is connected by a conductor 31 with the body of the engine, so that this strip 28 may be used for grounding the circuit of any one of the spark plugs, for when the spring 29 is pushed into engagement with the point or electrode 15, for example, the circuit of the spark plug corresponding thereto is grounded or short-circuited, and no current will be supplied to this plug. It happens, sometimes, although the sparking action on the indicator appears to be normal, indicating that all the plugs are receiving current, that the fuel in one of the cylinders is not being ignited and is not exploded. This may be for the reason that the spark plug has become foul and that, while it receives current, the sparking action is so interfered with that the fuel does not ignite in this particular cylinder. Of course, when one cylinder is thus out of order, and is not contributing to the power of the engine, the sound of the engine has a distinct character, and the sound will be changed if the spark plug of another cylinder is cut out by pushing one of the push buttons 30, for two cylinders will then be out of commission. Thus the different buttons can be pushed until one is found which does not change the sound of the engine and which, therefore, corresponds to the cylinder which is out of order, and thus the chauffeur or mechanic can readily determine which cylinder is out of commission. In this way, the ignition system is not only provided with means to indicate on the dash of the automobile the condition of each spark plug circuit, by making the current or spark visible, but means are also provided for at will controlling the supply of current to the different spark plugs, whereby any spark plug receiving current but at the same time not producing the proper ignition can be found. Furthermore, the spark gaps can be of a character to intensify the sparking action at the spark plugs, in the well-known manner, by using the metals which are well-known and well understood for this purpose, in the construction of the screws 10, 11, 12 and 13 and the upper electrodes 15, 16, 17 and 18, in a manner that will be readily understood. For example, steel is used for the electrodes of common or ordinary spark intensifiers, but any other metals which will produce this electrical effect, and which are known for this purpose, can be employed in

the construction of the points or electrodes which form the spark gaps of the indicator.

The indicator can be suitably mounted, and can be used on automobiles or motor boats, or any other place where it is desirable to indicate the condition of the ignition system of an internal combustion engine. 70

The invention is not limited to the exact construction shown and described. 75

What I claim as my invention is:

1. In combination with an internal combustion engine, and the ignition system thereof, a plurality of spark gaps arranged close together in a row, one for each cylinder of the engine, comprising metal elements spaced apart to form the gaps, a spring strip disposed adjacent to one element of each gap, means by which the strips are all grounded, a structure to support and insulate said metal elements and strips, and a push button for each spring strip, each button being operative to push its allotted strip into engagement with the adjacent element to ground the circuit of the corresponding gap. 80

2. In combination with an internal combustion engine, and the ignition system thereof, a plurality of spark gaps arranged close together in a row, one for each cylinder of the engine, comprising metal elements spaced apart to form the gaps, a reciprocating member arranged parallel with said row of gaps, metal means carried by said member and adapted for insertion in said gaps by the shifting of the member to stop the sparking, a handle to operate said member, and a structure to support said metal elements and member in operative relation. 95

3. In combination with an internal combustion engine, and the ignition system thereof, a pair of spaced metal elements forming a spark gap, metal means for insertion in the gap to stop the sparking, a single handle for operating said means, a device for engaging one of said elements to ground the circuit of the gap, said device being operable independently of said metal means, and a separate handle to operate said device. 100

4. A structure as specified in claim 3, in combination with one or more similar spark gaps, one for each cylinder of the engine, having similar metal means for insertion in each gap, all controlled and operated by said single handle, and a similar device and separate handle for each additional spark gap. 115

5. A structure as specified in claim 2, said member consisting of a strip of insulation, 120 and said metal means consisting of small portions of metal which are disposed in a row in the plane of said gaps and insulated from each other by said member. 125

6. A structure as specified in claim 2, said 130

- member being movable longitudinally and parallel with said row of gaps, and said metal means being disposed in the line of said row.
5. 7. In combination with an internal combustion engine, and the ignition system thereof, a spark gap, another spark gap, and reciprocating mechanism having means for insertion in each gap to stop the sparking action, said means having an inoperative position at one side of each spark gap, said engine having a spark plug corresponding to each spark gap, said mechanism including a plate of insulation having an 15 opening therein for each spark gap, a metal inset in said plate for each gap, forming said means to prevent the sparking, and a handle for shifting said plate to bring the openings thereof out of alinement with the 20 spark gaps, so that each gap will be occupied by its allotted metal inset.
8. In combination with an internal combustion engine, and the ignition system thereof, a plurality of spark gaps corresponding to the different cylinders of the 25 engine, a push button for each spark gap, a spring strip for each push button, each strip being adapted to be pushed against one side of the spark gap of its allotted 30 push button, means to electrically connect said spring strips together, means to ground said spring strips, insulating means to support the spark gaps, a reciprocating plate in said insulating means, said plate having an 35 opening for each spark gap, a handle for shifting said plate to bring the openings thereof out of alinement with the spark gaps, means on said plate for insertion in the spark gaps, thereby to stop the spark- 40 ing action, and means to mount the structure in the desired position.
9. A structure as specified in claim 2, in combination with means whereby one element of each spark gap is adjustable toward and away from the other element of 45 the gap, thereby to insure correct space between the elements for the reception of said metal means.
10. In an automobile internal combustion engine ignition system, the general combination of the following eight instrumentalities, to wit:—(1) a pair of oppositely arranged metal elements to form a spark gap in the circuit of each spark plug of the ignition system, (2) individual means for 50 grounding one side of each spark gap, having a separate handle for each gap, so that each spark plug circuit can be grounded independently of the others, (3) metal means for insertion in said spark gaps to stop the 55 sparking without interrupting the flow of current in the different spark plug circuits, (4) a single operating handle for said metal means, common to all of said gaps, whereby said metal means are operable independently of said grounding means, (5) a structure of insulation forming a support for 60 said metal elements, (6) means to support said structure in position on the dash of the automobile, (7) a grounding connection 65 leading from said individual means, and (8) circuit connections leading from said metal elements to the spark plugs and the distributor of the ignition system.
- Signed by me at Chicago, Illinois, this 75
25th day of August, 1917.

JULIUS J. MILLER.
